UNITED STATES PATENT OFFICE.

ALVIN J. GRAFFIN, OF MONTCLAIR, NEW JERSEY, ASSIGNOR TO GRAFFIN & DOLSON, OF NEW YORK, N. Y., A COPARTNERSHIP.

DESIGN FOR A TEXTILE FABRIC.

53,364.

Specification for Design.

Patented May 27, 1919.

Application filed November 25, 1918. Serial No. 264,111. Term of patent 7 years.

To all whom it may concern:

Be it known that I, ALVIN J. GRAFFIN, a citizen of the United States, residing at Montclair, in the county of Essex and State of New Jersey, have invented a new, original, and ornamental Design for a Textile Fabric, of which the following is a specification, reference being had to the accompanying drawing, forming part thereof.

The figure is a face view of a portion or strip of textile fabric showing my new design.

I claim the ornamental design for a textile fabric as shown.

ALVIN J. GRAFFIN.

Witnesses:

DYER SMITH,
I. MCINTOSH.
